UNITED STATES PATENT OFFICE.

RYUJI SATO, OF NEW YORK, N. Y.

GAME.

1,277,263.

Specification of Letters Patent. Patented Aug. 27, 1918.

Application filed August 31, 1917. Serial No. 189,172.

To all whom it may concern:

Be it known that I, RYUJI SATO, a citizen of the United States of America, residing at New York city, in the county of New York 5 and State of New York, have invented new and useful Improvements in Games, of which the following is a specification.

This invention relates to game boards and has particular reference to a game board 10 which simulates substantially the game base ball.

The primary object of the invention is the provision of a board over the surface of which balls are adapted to be rolled, said 15 surface being provided with substantially diamond shape groove having counting pockets arranged in the corners thereof with obstructing pockets distributed between the counting pockets and penalizing pockets distributed over the surface of the board whereby the players are afforded amusement as 20 well as practice in the skilful manipulation of the balls over the surface of the board and into the counting pockets.

25 A still further object of the invention is the provision of a game board of the class described which is provided with playing surfaces arranged on both sides thereof whereby the same may be used for different 30 games by reversing the board.

With these and other objects in view, the invention resides in the novel construction, combination and arrangement of parts which are fully described in the following 35 description particularly pointed out in the appended claims and clearly illustrated in the accompanying drawings, of which

Figure 1, is a plan view of the board.

Fig. 2, is a similar view of the reverse 40 side thereof.

Fig. 3, is a vertical longitudinal section there-through.

Fig. 4, is a transverse section, and

Fig. 5, is a sectional view on the line 5—5, 45 of Fig. 2.

Referring to the drawings by numerals, 10 represents a base board having playing surfaces 11 and 12, which are confined or surrounded by a frame member 13. The 50 base member 10, is secured within the frame 13, by means of strips 14—14. The surfaces of the base member are provided with diamond shape grooves 15, at the corners of which are arranged the counting or registering pockets 16. Said pockets simulating home plate, first base, second base and third

base as in the usual game of base ball. These pockets may be of different values in playing the game. Distributed within the grooves between the counting pockets are a 60 series of obstructing pockets 17, which serve to add to the difficulties of rolling the ball into the counting pockets as will be clearly understood. Distributed over the surface of the base are a plurality of penalizing 65 pockets 18, which are arranged within the diamond shape groove as well without and which substantially represent the different fielding plays in the game of base ball. If preferable the board may be made on a large 70 scale for instalment in amusement parks. A ball or plurality of balls 19, are used for the playing of the game and a ledge 20, may be secured to the surface of the base to confine a retaining pocket 21, for the balls 75 which are not in play. It will be noted from Fig. 5, that the counting pockets 16, are of substantially greater depth than the obstructing pockets 17. The game may be played in any number of ways but I do not 80 care to be limited to the exact method of play.

For the purpose of illustrating one method of playing the game, the ball 19, is placed in the counting pocket 16, representing the home plate. The player by tilting the board then seeks to move the ball over the playing surface to the far end of the same and back again to the home plate, without allowing the ball to enter the penalizing pockets 18. If this is accomplished, he is allowed to roll the ball through the groove to the first counting pocket 16, which represents home plate to the right hand pocket 16 representing first base and thence 90 to the second, third and home plate, thus scoring one run. If the ball, during its travel over the playing surface enters any one of the penalizing pockets 18, within the diamond or in the outfield, an out is registered and the player continues until three outs have been scored against him. Presuming the playing piece has been successfully rolled over the playing surface to the far end and back to the home plate, the 105 player now attempts to advance the same to first base, second base, third base and home respectively, but if in so doing the ball be deflected from the groove 15, by the obstructing pockets 17 and enter any of the 110 penalizing pockets 18, an out is registered.

From the foregoing description taken in

connection with the drawings it will be seen that I have shown and described a simple and preferred form of the invention but I desire to have it understood such changes, 5 alterations and modifications that fall within the scope of the appended claims may be resorted to when desired.

What I claim is:

1. A game board comprising a base and 10 side walls confining a playing surface, a diamond shape groove arranged in said base, counting pockets arranged in said groove, obstructing pockets arranged between said counting pockets and penalizing pockets 15 distributed over the remaining surface of the base.
2. A game board comprising a base, arranged within a frame and equally spaced therefrom to provide a plurality of playing 20 surfaces, a diamond shape groove arranged in each surface of said base, counting pockets arranged in said grooves, obstructing pockets arranged between said counting pockets and penalizing pockets distributed 25 over the remaining surfaces of the bases.
3. A game apparatus comprising a member having a playing surface, said surface having the simulation of a base ball diamond arranged therein and defined by continuous groove, the said surface having cavities therein at the intersection of the several 30 angles of said grooves with each other and representing base positions, the said dia-

mond simulating portion being located at one end of said member, the portion of the 35 member within the margin of the groove being flush with the upper surface of the member beyond said groove, the said member having a multiplicity of cavities arranged forwardly of the groove and at the 40 sides and the rear thereof and a playing element adapted to be projected over the playing surface of said member as and for the purpose specified.

4. A game apparatus comprising a member having a playing surface, said surface having the simulation of a base ball diamond arranged therein and defined by continuous groove, the said surface having cavities therein at the intersection of the 45 several angles of said grooves with each other and representing base positions, the said diamond simulating portion being located at one end of said member, the portion of the member within the margin of the groove being flush with the upper surface of the member beyond said groove, the 50 said member having a multiplicity of cavities arranged forwardly of the groove and at the sides and the rear thereof and a playing element adapted to be projected over the playing surface of said member and other cavities and openings into said groove between said base position.

In testimony whereof I affix my signature. 55

RYUJI SATO.
